UNITED STATES PATENT OFFICE.

ARTHUR JUNGHANS, OF SCHRAMBERG, GERMANY.

MECHANICAL TIME-FUSE.

1,069,094.

Specification of Letters Patent.

Patented July 29, 1913.

Application filed March 10, 1913. Serial No. 753,461.

To all whom it may concern:

Be it known that I, ARTHUR JUNGHANS, privy commercial councilor, subject of the King of Wurttemberg, residing at Schramberg, in the Kingdom of Wurttemberg, Germany, have invented certain new and useful Improvements in Mechanical Time-Fuses, of which the following is a specification.

10 My invention relates to a mechanical time-fuse, for artillery projectiles, driven by a centrifugal weight.

Most of the well-known mechanical time-fuses for artillery projectiles are provided 15 with spring-driven clockwork. This mode of driving has certain disadvantages which are detrimental to practical employment on a large scale, particularly the two defects that, firstly the uniformity of the delivery 20 of energy disappears as the tension of the spring decreases and, secondly, the tension of the spring suffers during storage. According to my invention, therefore, I use as the driving force for the clockwork not the 25 spring, but the centrifugal force of a weight.

Time-fuses using the centrifugal force of a weight have frequently been proposed heretofore. If they are to be of practical value, however, they necessitate the interpolation of devices by means of which, in spite of variation of the magnitude of the centrifugal force during the running of the clock mechanism the magnitude of the driving force is caused to remain constantly un- 30 changed. In well-known arrangements of this type the driving force of the centrifugal weight is intended to be equalized by a spring, but exact regulation cannot be obtained by such means because the spring in 35 this case precludes all calculation. My invention is characterized by the clockwork being entirely freed from a spring and its unavoidable disadvantages, the action of the centrifugal force of the centrifugal weight 40 being regulated in a predetermined manner by varying its effective moment without the aid of a spring. The reason of the non-uniformity of the driving force in the case of a drive by means of the centrifugal weight 45

50 is due to the fact that as the weight swings outward, the moment of the force increases with the increasing distance from the longitudinal axis of the projectile. According to my invention this non-uniformity is equal- 55 ized by means acting to produce an exactly predetermined variation of the moment of

the force. In one embodiment of my invention I effect this by means of an auxiliary centrifugal weight which, at the commencement of the movement, aids the main weight, 60 but subsequently opposes it, so that a constantly uniform delivery of energy is assured. In another form of my invention the main weight coacts with an intermediate disk having a spiral periphery which is so 65 connected with a disk on the driving shaft of the clock-work that in spite of the greater force of the centrifugal weight in consequence of its increasing distance from the axis of the projectile, the moment of the force is 70 kept uniform by diminishing the length of the lever arm through which it acts on said clock-work driving-shaft. Such spiral intermediate disks (so-called worms) are already well known for regulating the driving 75 force of spring driven clock-work.

The two described forms of my invention are represented in the accompanying drawing, wherein:

Figure 1 is an elevation showing one form, 80 and Fig. 2 is a like view showing the other form. Fig. 3 is a vertical sectional view of a fuse-mechanism showing the present invention applied thereto. Fig. 4 is a horizontal sectional view on the line 4—4 Fig. 35 3 with parts broken away to show some of the under-lying mechanism.

Referring firstly to Fig. 1, the centrifugal weight p is fast on a toothed segment a pivoted at a^1 which gears with a 90 pinion c^1 fast on a shaft c connected to a clock-work W (Fig. 3) carrying a disk R for controlling the operation of a firing pin F . The shaft c is also suitably geared to a toothed disk b carrying an auxiliary 95 centrifugal weight p^1 . As long as the auxiliary weight p^1 moves away from the axle c (Fig. 1) its action aids the weight p with a tangential component of its centrifugal force. This augmentation becomes smaller 100 in proportion as the weight p^1 moves outwardly. In the position 2 of the weight p^1 this tangential component becomes equal to zero; on the way from position 2 to 3, (during which time the centrifugal force 105 and consequently the driving force of the weight p is constantly increasing), the negative value of the component of the weight p^1 constantly increases. By this means a practically constant torque is produced on 110 the shaft c . In other words, the auxiliary weight p^1 has a variable moment for com-

pensating for variations in the centrifugal force of the said centrifugal element p .

The rotation of the projectile, when fired from a gun, produces a revolution of the 5 weights p and p^1 around the axis of the projectile, and the centrifugal force produced thereby transmits a turning force to the shaft c through the toothed segment a , disk b , and pinions d , e . Rotation of the shaft c 10 is regulated by an escapement E through a train of gears f , g , h , i , the shaft c thereby having a slow movement. The shaft c carries at its upper end a disk R , which moves 15 with it, as in well-known fuses of the present type. The disk R has a notch r therein, in which a detent H can fall when the notch r comes opposite the detent. The detent r controls the operation of a pivoted lever L which has at one end a stop l which in turn 20 controls the operation of a second detent O , controlling the operation of a pin P . The pin P controls the outward movement of a slide S engaging the under side of the spring-pressed firing pin F . Consequently, 25 when the shaft c is turned a sufficient amount to bring the notch r in disk R opposite the detent H , the detent H will fall in the notch, and release the lever L , the lever L will in turn release the detent O , and this will permit 30 the pin P to rise, which will release the slide S and permit the spring to press the firing pin F into firing contact with the fulminating cap of the shell.

In the form according to Fig. 2 the 35 toothed segment a carrying the centrifugal weight p acts through a pinion c^1 on a disk b^1 which drives through the medium of a tie, *e. g.* a fine chain, silk thread, coiled steel string or the like, a drum or disk b^2 40 fast on the shaft c and having a conical thread or a spiral on its periphery. As the centrifugal force of the weight p becomes greater the tie leaves the disk b^2 at a radius which constantly becomes smaller, 45 whereby the effective moment of the force transmitted to the mechanism by the shaft c remains constant when the conditions are suitably selected.

In both the described forms, instead of 50 only one toothed segment a a second toothed segment a^1 having a weight p^2 may be arranged in addition, whose action is to assist the weight p either during the entire movement or, as represented in Fig. 2, only 55 at first during the initial part of the movement of said weight p .

What I claim as my invention and desire to secure by Letters Patent is:

1. A driving mechanism for time fuses 60 comprising a driving-shaft of a clock-work, a centrifugal element adapted to receive force from the rotation of a projectile when fired

from a gun, and to impart force to said driving shaft and means having a variable moment for compensating for variations in 65 the centrifugal force of said centrifugal element.

2. A driving mechanism for time fuses comprising a driving shaft of a clock-work, a centrifugal element adapted to receive 70 force from the rotation of a projectile when fired from a gun, and to impart force to said driving shaft, and means modifying the force exerted by said centrifugal element upon said driven part, said means 75 transmitting force to said driving shaft through a variable moment.

3. A driving mechanism for time-fuses comprising a driving shaft of a clock-work, a centrifugal element adapted to receive 80 force from the rotation of a projectile when fired from a gun, and to impart force to said driving-shaft, and a second centrifugal element adapted to compensate for variations in the effect of said first centrifugal 85 element upon said driving-shaft.

4. A driving mechanism for time fuses comprising a driving-shaft of a clock-work, a centrifugal element adapted to receive 90 force from the rotation of a projectile when fired from a gun, and to impart force to said driving-shaft, and a second centrifugal element adapted to compensate for variations in the effect of said first centrifugal 95 element upon said driving-shaft through a moment variable with relation to that of the first.

5. A driving mechanism for time fuses comprising a driving-shaft of a clock-work, a centrifugal element adapted to receive 100 force from the rotation of a projectile when fired from a gun, and to impart force to said driving-shaft, and a second centrifugal element adapted to compensate for variations in the effect of said first centrifugal 105 element upon said driven part, said second centrifugal element comprising a pivoted weight.

6. A driving mechanism for time fuses comprising a driving-shaft of a clock-work, 110 a centrifugal element geared with said driving shaft and adapted to impart force thereto, and a second centrifugal element also geared to said driving-shaft and adapted to compensate for variations in the effect of 115 said first centrifugal element by force applied through a moment variable with relation to that of the first.

In testimony whereof I have affixed my signature in presence of two witnesses.

ARTHUR JUNGHANS.
